E. J. JOHNSON

CONTROLLING MECHANISM FOR WINDOWS AND OTHER MOVABLE MEMBERS

Filed Sept. 21, 1922

Fig. 1.

Inventor.
Eric J. Johnson,
By myself, L. Clinton Mills,
Attest,

UNITED STATES PATENT OFFICE.

ERIC J. JOHNSON, OF CHICAGO, ILLINOIS.

CONTROLLING MECHANISM FOR WINDOWS AND OTHER MOVABLE MEMBERS.

Application filed September 21, 1922. Serial No. 589,597.

To all whom it may concern:

Be it known that I, ERIC J. JOHNSON, a citizen of the United States, residing at Chicago, in the county of Cook and State of Illinois, have invented a new and useful Improvement in Controlling Mechanism for Windows and Other Movable Members, of which the following is a specification.

My invention was devised more particularly for use in controlling the position occupied by a casement window, though it will be understood from the following description that it may be applied to use in connection with any movably-supported member of such character as to be controlled thereby.

One of my objects is to provide a novel, simple and inexpensive construction of mechanism whereby the movable member to be controlled thereby may be quickly actuated to the desired position. Another object is to provide for the holding of the member in the position to which it is actuated and, in the case of a casement window or the like, to positively hold it in both open and closed positions; another object is to provide for the quick movement of the member and preferably the holding of the member in adjusted position and, in the case of a casement window, holding it in closed position; and other objects as will be manifest from the following description.

Inasmuch as I have devised my invention for use more particularly in connection with casement windows, I have chosen to illustrate it as applied to such use in the accompanying drawing, though not with the intention of limiting the invention thereto.

Referring to the accompanying drawings: Figure 1 is a plan sectional view of a casement window together with the window casing to which my improved controlling mechanism is applied, the mechanism being shown in plan; the window in this figure is shown in closed position. Figure 2 is a view like Fig. 1 showing the window partly open. Figure 3 is a section taken through a part of the controlling device, the section being taken at the line 3 on Fig. 5 and viewed in the direction of the arrow. Figure 4 is a section taken at the line 4 on Fig. 2 and viewed in the direction of the

arrow; and Figure 5, a plan section of a part of the controlling mechanism referred to.

In the particular arrangement shown the frame of a casement window is represented at 6, the casement window being shown at 7, the latter being hinged along one vertical edge thereof to the window casing, in accordance with common practice, as represented at 8, to adapt the window to be swung outwardly.

The particular illustrated embodiment of my invention comprises a bearing member 9 shown as formed of an inverted cup-shaped member 9 telescoped with the upwardly-extending circular flange 10 of a base member 11 flatwise secured to the sill of the window frame, as by the screws 12. The member 9 which is thus swiveled upon the base member 11, adapting it to oscillate thereon, is held against vertical displacement in any suitable manner, as, for example, by screws 13 carried by the member 9 and extending at their inner ends into a peripheral groove 14 located in the flange 10. The member just described serves as a bearing for a rod 15 which extends diametrically therethrough and is journaled therein, the rod 15 being shown as provided with a sleeve 16 located within the member 9 and secured to the rod 15, against relative longitudinal movement, as by means of a screw 17 passing through the sleeve and into an opening in the rod, this sleeve therefore preventing longitudinal movement of the rod. It is preferred that the sleeve 16 be provided with a plurality of the screw-receiving openings, one of which is shown at 18, for receiving the screw 17, whereby the position of the rod 15 lengthwise, in the member 9, may be varied, to suit different conditions.

The rod 15 is provided at the end thereof between the bearing member 9 and the window 7, with a spiral groove provided on its periphery, different portions of this groove being of different pitch. In the construction shown the portion of the groove adjacent the bearing member 9 is of relatively short pitch, this portion being shown at 19; and the portion of the groove therebeyond, and represented at 20, is of relatively great pitch, as represented. The rod 15 extends, at its

grooved portion, into a tube 21 in which it is rotatable, this tube being pivoted, as indicated at 22, to the spaced ears 23 of a clip 24 secured to the inner face of the window 7, the tube 21 being provided with a pin 25 which extends into the spiral groove in the rod 15. The opposite end of the rod is provided with a knurled head 26 to facilitate the rotating of the rod by the operator, this end of the rod being provided with a collar 27 rigidly secured to a pin 28 shown as in the form of a key, lengthwise movable in a groove 29 in the rod 15 and extending lengthwise thereof, the wall of the member 9, adjacent the one of the openings therein in which the rod 15 is journaled, containing a notch 30 adapted to receive the key 28. In the closed position of the window (Fig. 1), the pin 25 extends into the portion 19 of the spiral groove, and by reason of the relatively slight pitch of this groove, a great resistance to the opening of the window except through the manipulation of the device described, is presented, and this holding effect may be augmented, if desired, by the operator sliding the collar 27 to a position in which the key 28 enters the notch 30. To open the window, the operator rotates the rod 15 in counter-clockwise direction in Figs. 3 and 4, with the result of causing the pin 25, together with the tube 21 and the window 7, to be forced away from the bearing member 9, the window swinging outwardly on its hinges 8. In this movement of the rod 15, the pin 25 travels over the portion 19 of the spiral groove into the portion 20 of this groove, and as the latter is of relatively great pitch, the window is caused to swing outwardly at relatively great speed, or, in other words, it requires only a comparatively few turns of the rod 15 to swing the window to fully extended position. Any suitable means may be provided, if desired, for preventing accidental closing of the window, as, for example, by the action of wind, the means above referred to, and of which the key 28 is a part, serving this purpose, these locking means, or other locking means for preventing the rod 15 from being reversely rotated, being especially useful in the holding of the window 7 in a position of adjustment intermediate its full open and closed positions.

The movement of the window 7 to closed position involves, as will be manifest, the rotation of the rod 15 in clockwise direction in Figs. 3 and 4, the projection 25 traveling in the spiral groove in the rod. The window will thus be caused to be swung substantially to closed position by a comparatively few turns of the rod. In the final rotation of the rod, however, the pin 25 enters the portion 19 of the spiral groove whereby the desirable amount of leverage 65 between the rod and the window is pre-

sented for drawing the window into tightly closed position and holding it firmly against accidental outward movement, the releasable locking means referred to being used if desired. 70

It will be understood that where my improvement is used in connection with a pivotally-supported window, as in the construction shown, the provision of the swivelled bearing member 9 permits of the 75 swinging of the rod 15, while maintaining journal connection therewith in the opening and closing of the window.

It has been above suggested that the connection of the rod 15 with the bearing member 9 through the sleeve 16, permits of the adjustment of the rod 15 in this bearing member. It will be understood in this connection that by reason of the proportioning of the parts of the window frame or other 85 condition presented, it may be desirable to position the bearing member at a greater distance from the window than as shown in the drawings. If it is necessary that the bearing member be moved farther away 90 from the window than as shown, the rod 15 would be adjusted lengthwise in the bearing member 9 to a position in which the opening 18 would register with the opening in the rod 15 for receiving the screw 17 and 95 the sleeve secured in this position. Any desirable number of the adjustments referred to may be provided.

While I have illustrated and described a particular construction embodying my invention, I do not wish to be understood as intending to limit it thereto as the same may be variously modified and altered without departing from the spirit of my invention. 100

What I claim as new, and desire to secure 105 by Letters Patent, is:

1. In a device of the class described, in combination, a frame having a stop member, a closure pivotally mounted on said frame and impinging against said stop member, a rod having a spiral groove of varying pitch, a sleeve, one of said last named elements pivotally mounted on said frame and the second thereof pivotally connected to said closure, a stud rigidly carried by said sleeve and engaging said groove, the portion of the groove of least pitch coacting with said stud when the closure engages said stop member whereby to cause firm engagement thereof, means to cause relative rotation between said rod and sleeve, and releasable locking means to prevent reverse rotation of said rod. 110

2. In a device of the class described, in combination, a threaded member, a tubular member having means to coact with the thread of the first named member, a turret, means to mount said turret for free rotation, one of said members passing through the walls of said turret, means within the turret and secured to said member prevent- 115 120 125 130

ing axial movement and permitting rotation of said member and means for pivotally attaching the other member to a hinged closure.

5 3. In a device of the class described, in combination, a threaded member, a tubular member having means to coact with the thread of the first named member, a turret, means to mount said turret for free rotation,

one of said members passing through the 10 walls of said turret, means within the turret and secured to said member preventing axial movement and permitting rotation of said member, means to lock said rotatable member to prevent rotation thereof, and means 15 for pivotally attaching the other member to a hinged closure.

ERIC J. JOHNSON.
